Inventor:
Clarence H. Chubbuck
by *W. Steele Jr.* Attorney

UNITED STATES PATENT OFFICE.

CLARENCE H. CHUBBUCK, OF CYNWYD, PENNSYLVANIA, ASSIGNOR TO McCLINTIC-MARSHALL COMPANY, OF PITTSBURGH, PENNSYLVANIA, A CORPORATION OF PENNSYLVANIA.

FLOOR-TROUGH STRUCTURE FOR BRIDGES.

Application filed December 6, 1922. Serial No. 605,178.

To all whom it may concern:

Be it known that I, CLARENCE H. CHUBBUCK, a citizen of the United States, residing at Cynwyd, in the county of Montgomery and State of Pennsylvania, have invented a certain new and useful Floor-Trough Structure for Bridges, of which the following is a specification.

My invention relates to floor trough structure for bridges.

The purpose of my invention is to build the troughs of bent plates as distinguished from rolled metal shapes.

I thus secure easy and inexpensive manufacture with the equipment of the ordinary bridge shop, along with great flexibility of construction to suit any desired spacing between trough centers, any desired depth of trough and any angle of webs necessary to use plates in stock or readily obtainable from current rollings by the mills.

At the same time I maintain a high moment of inertia and a low weight of metal per lineal foot of trough section.

A further purpose is to facilitate the use of different thicknesses of metal for the web and flange elements respectively of the trough.

Further purposes will appear in the specification and in the claims.

I have preferred to illustrate my invention by but three forms, selecting these forms because of their practicability and desirability from different standpoints and particularly because they well illustrate the principles of my invention.

Figure 1 is a fragmentary vertical section upon line 1—1 in Figure 2, illustrating one form of my invention.

Figure 2 is a fragmentary section upon line 2—2 of Figure 1.

Figure 3 is a fragmentary top plan view of the structure seen in Figures 1 and 2.

Figures 4 and 5 are fragmentary sections through the troughs and show other forms of my invention.

Figures 6 and 7 are fragmentary sections of the troughs of Figures 1 and 5 respectively modified by having the horizontal plates at top and bottom heavier than the inclined plates.

Figure 8 is a perspective view of a flat

plate intended to be bent to form a wall of my trough.

Figure 9 is a perspective view of the structure of Figure 8 after bending.

Figures 10 and 11 are top plan views showing my bridge flooring applied to curves in single tracks.

Figures 12 and 13 are plan views of plates used respectively in Figures 10 and 11.

Figure 14 is an end elevation of the plate shown in Figure 13.

In the drawings similar numerals indicate like parts.

Describing in illustration and not in limitation, and referring to the drawings:

I have shown my trough floor as used on a deck plate girder span in which the plate girders are shown at the sides 10 and which are connected by the angle cross frames 11 through gusset plates 12 joined horizontally at top and bottom by the angles 13.

My trough structure is adapted to any form of span and the foundation deck plate girder span is shown merely as an example of one form to which it may be applied.

Upon the foundation deck plate girder span I place the trough floor, and in the illustration the trough sections are spaced to correspond with the spacing of the ties 14 for rails 15. The concrete and ballast with or without waterproofing is shown at 16.

Prior to my invention a number of different trough floor elements have been proposed and used, generally based on the use of rolled angles and plates or rolled Z's and plates. The general railroad practice is now and for many years has been confined to some such combination.

All of these forms are objectionable as requiring separate sizes and in most cases different angles of rolled shapes, for each different depth of trough or spacing between trough centers.

In bridge building it is necessary to meet varying needs and widely different specifications, particularly in the case of railroads, which differ in their practice sometimes even in the same country and whose standard practices vary widely in different countries. The largest factor in this is the variation in the spacing between railroad ties,

- making it necessary to have different spacing between the trough sections. Because of this and sometimes of other considerations, the depth of the trough sections vary widely.
- 5 The requisite standard forms for floor elements with diagonal webs are frequently very hard to get, are expensive to fabricate and are unsuited to meet conditions which are not standard.
- 10 I avoid unnecessary delay, undue expense and faulty adaptation to conditions not standard by providing a bent plate structure adapted to easy and inexpensive manufacture from material and with appliances available in ordinary bridge shops and adapted to meet readily any of the varying specifications with respect to trough spacing, trough depth and inclination of the trough walls.
- 15 20 Where diagonal webs are desired another fault of said prior structures has been the placing of excessive metal in the middle, along the plane of neutral strain, where it is not needed and has but little effect toward strengthening and stiffening the floor. The result has been a low moment of inertia and a consequent unnecessarily low strength for a given weight of material per lineal foot.
- 25 30 In my bent plate floor, along with diagonal webs I avoid this low strength by placing the lap joints at the top and bottom instead of in the middle, thus obtaining material increase in the moment of inertia and consequently in the strength for a given weight of metal; and moreover am able to use heavier plates at the top and bottom than at the sides to still further increase the moment of inertia for a given weight of material.
- 35 40 While my bent plate floor has been designed primarily for railroad bridges it is likewise well adapted to highway bridges, advantageously and inexpensively replacing, for example, the usual types of trough flooring.
- 45 50 As all of my plates are initially flat they may be sheared from larger plates and tapered plates (Figure 1) can be prepared as readily as straight. The shears, presses, punches and riveters required are all standard shop tools.
- 55 In the form shown in Figure 1 I use bent plates which may be exactly alike where the top and bottom plates need not be heavier than the inclined web plates and which are bent up from flat parallel-edge plates 17 by bending along the lines 18 to form flanges 19.
- 60 The plates are shown in Figure 1 as all alike and interchangeable, but obviously this may be varied by using lighter plates for the inclined plates at 23 than for the horizontal plates at 23', as shown in Figure 6, which would further increase the moment of inertia of the structure for a given weight of material. The moment of inertia is al-

ready high from placing the lap joints of the structure near the top and bottom.

In Figure 1 the horizontal plates at top and bottom lie respectively above and below the ends of the diagonal plates to desirably increase the depth. Following the nomenclature of a floor in which the bent flanges are at the right in all the plates, the bent flanges 22 of the top plates overlap at the right and are secured to the edges of flat portions 23 of the adjoining diagonal plates whose bent flanges correspondingly overlap but lie above the flat plate portions 23 of the bottom sections. The bent flanges 22 of these bottom sections lie to the left of the flat portions 23 of the next diagonal plates whose bent flanges 22 lie beneath the flat portions of the top plates. It will be obvious that these could run equally toward the left instead of toward the right with the flanges extending toward the left instead of toward the right with equal advantage.

All of these bent plates are riveted as at 24 through punched or drilled holes 25 and, as will be seen, give half the number of overlaps in or against the plane of the top and bottom plates and the remaining overlaps in the diagonal section closely adjoining the top and bottom plates, securing a very high moment of inertia.

It is best to have the trough sections flared rather than straight to give ample room for riveting and also because the flaring sections are better adapted to use with concrete.

The holes for the rivets 24 may be punched either before or after bending the plates. All of the joints are riveted. The trough structure, as usual, is riveted to the back of the girder 10.

In the form of floor illustrated in Figure 4 the horizontal plates 26 and 27 are of trough shape, having both sides of the plates bent to form flanges diverging one from the other; and the inclined plates 28 are flat making lap-joints with the diagonal flanges of the top and bottom plates.

This form of Figure 4 does not place the lap-joints as advantageously for high moment of inertia as in the forms of the other figures as the joints are less distant here from the plane of neutral stress than in the forms of these other figures.

This form has the added disadvantage of being difficult to rivet up in sections. It has the advantage that the rivets do not project here beyond the horizontal bottom and top plates, which is sometimes desirable. The top and bottom plates can be made of different thickness if desired from the thickness of the inclined plates.

In the form of Figure 5 the horizontal plates 29 are flat and the inclined plates 30 are bent adjacent both edges, one to the

right and the other to the left in the illustration to provide lap-joint engagement with the horizontal plates, which latter lie respectively above and below the flanges of the inclined plates or webs.

The forms shown in Figure 1 and Figure 5 lend themselves well to use also where the top and bottom plates (flanges) are desirably of different thickness from the webs and these constructions are shown in Figures 6 and 7 respectively. In Figure 6 the top and bottom plates 23' are of heavier bent plates than are the webs 23 and in Figure 7 the plates 29' are of greater thickness than the webs 30'.

The form of Figures 5 and 7 is somewhat better than either of the other forms shown in having the lap-joints all in the horizontal portions of the top and bottom with a resultant somewhat greater strength and stiffness for a given weight of material.

Because my plates are initially flat they can be bent from tapered plates as readily as from plates having parallel edges, adapting my flooring to use in joining skew spans. They are specially suited for this because either edge of any plate can be bent at any angle to the main plane of the plate, to connect up with the existing forms so as 30 to unite with the skew ends to the best advantage.

The same capability of tapering plates adapts my flooring to bridges upon which curved tracks are to be laid and I have shown two forms of this in Figures 10 and 11 respectively. In these figures the bridge spans are omitted, and the flooring only appears in full lines.

In Figure 10 tapered plates 23² are used for the top plates only, of a floor corresponding except for the tapering to that in Figure 1. It will be noted that the entire tapering is effected in the top plates, leaving the troughs of uniform width and slope throughout their lengths.

In Figure 11 the form of trough section seen in Figure 5 is used and the tapering is divided between the top and bottom plates, 29², slightly tapering the widths of the troughs as well as the spaces between them.

It will be evident that in all of my structures the use of bent plates brings the construction within the range of the tools in an ordinary bridge shop and permits varying the thickness of metal in the horizontal and inclined portions respectively; that it permits varying the spacing between trough sections, that it places the overlapping metal sections close to the top and bottom, thereby obtaining high moment of inertia, and that it permits substitution of parts made at the point of erection in case of defects found in any of the plates.

In view of my invention and disclosure, modifications and variations may well occur

to others skilled in the art to meet particular need or individual whim and I purpose including herein all such modifications and variations in so far as they fall within the reasonable spirit and scope of my claims. 70

Having thus described my invention, what I claim as new and desire to secure by Letters Patent is:—

1. A metal trough floor for bridges comprising plates of uniform shape united to form top and bottom plates and webs respectively and having the overlapping portions of the webs beneath the top and above the bottom of the top and bottom plates. 75

2. In a metal trough floor, top and bottom plates and webs, each comprising flat plates bent at one side only and having the bent edge at the same side of the plates and webs across the section of the floor, the body of each plate and web being united to the flange 85 of the adjoining member.

3. A metal trough floor for bridges comprising a plurality of flat plates bent to form diagonal flanges and having the body parts of the plates, forming the horizontal top and bottom flanges of the troughs, joined by diagonal plates of like shape. 90

4. A metal trough floor for bridges comprising a plurality of flat plates bent to form diagonal flanges and having the body part 95 of each plate overlapping and riveted to the flanged part of the adjoining plate.

5. In a metal trough floor, the combination of a plurality of plates comprising flat portions and angular flanges and having the 100 angular flanges progressively connected to the flat portions of the adjoining plates from plate to plate.

6. A metal trough floor for bridges having horizontal trough flange members and connecting webs, made up of trough flange and web members of the same shape but having greater thickness in the trough flanges than in the webs. 105

7. In a metal trough floor for bridges having horizontal trough flange members and diagonal webs, the combination of a plurality of bent plates of the same shape in cross section and connected at their adjoining edges to form the flanges and the webs of the 115 troughs.

8. In a metal trough floor for bridges having horizontal trough flanges and diagonal webs, the combination of a plurality of horizontal and diagonal members comprising plates bent at their edges diagonally to the bodies of the plates and having the web members of the troughs connected wholly beneath the top trough flange members and wholly above the bottom trough flange members. 120

9. In a metal trough floor for bridges having horizontal trough flanges and diagonal webs, the combination of bent plates at the top and bottom of the troughs, forming the 130

flanges, having their bent portions extending diagonally in a downwardly and an upwardly direction respectively, and diagonal bent plates connecting these plates and forming the webs and having their bent portions extending horizontally for connection with the plates.

10. In a metal trough floor for bridges having horizontal trough flanges and diagonal webs, flat top and bottom trough flange plates bent along one edge each, in combination with web plates of corresponding form but different thickness riveted to the flange

plates so that the bent portion of one plate is riveted to the body portion of the adjoining plate.

11. A metal trough floor for bridges comprising flat top and bottom members, each flanged at one side, in combination with web members each flanged at one side, the flanges of the web members being connected beneath the top and above the bottom of the body portions of the top and bottom members and with the bodies of the webs connected to the flanges of the top and bottom portions.

CLARENCE H. CHUBBUCK.
